CARD FILE TABLE

Carl G. Dahlgren, Chicago, Ill.

Application August 26, 1954, Serial No. 32,028

Term of patent 14 years

(Cl. D33—14)

Fig. 1 is a front perspective view of a card file table showing my new design as it appears with two of the cover panels removed and stacked at the sides of the table legs;

Fig. 2 is a rear perspective view thereof as it appears with the panel covers in closed position;

Fig. 3 is a front elevational view of the card file table as shown in Fig. 1; and

Fig. 4 is a cross sectional view taken on line 4—4 of Fig. 2.

I claim:

The ornamental design for a card file table, substantially as shown.
